UNITED STATES PATENT OFFICE.

WILLIAM G. LIEBIG, OF DETROIT, MICHIGAN.

BRISTLE-FEEDING MEANS FOR BRUSH-MAKING MACHINES.

No. 920,355.

Specification of Letters Patent.

Patented May 4, 1909.

Application filed August 3, 1906. Serial No. 328,977.

To all whom it may concern:

Be it known that I, WILLIAM G. LIEBIG, a citizen of the United States, residing at Detroit, county of Wayne, State of Michigan, 5 have invented a certain new and useful Improvement in Bristle-Feeding Means for Brush-Making Machines, and declare the following to be a full, clear, and exact description of the same, such as will enable 10 others skilled in the art to which it pertains to make and use the same, reference being had to the accompanying drawings, which form a part of this specification.

This invention relates to bristle feeding 15 means for brush making machines, and has for its object an improved receptacle and bristle manipulator whereby the bristles are fed forward in a mass against the engaging periphery of the bristle carrier, which automatically selects from the mass the quantity 20 of bristles desired for a tuft, and carries the same to its point of deposit in the vicinity of the brush back, into which it is stapled, and at each stroke of which the bristles remaining 25 in the mass in the feed box are pushed back to their proper position.

The device of this application is equally adjustable to either of my Patents No. 845,959, dated March 5, 1907, or No. 846,583 30 dated March 12, 1907.

In the drawings:—Figure 1, is an elevation, from the rear of the machine, of the feed box and the bristle sweep, together with enough of the movable portion of the 35 mechanism to show the means of operating the sweep. Fig. 2, is a front elevation of the feed box and sweep, together with the adjacent portions of the machine, the relative position of the bristle carrier and of the 40 sweep, with reference to the adjacent parts, being shown respectively in full lines and in dotted lines. Fig. 3, is a perspective from the rear of the feed box, disassociated from the other portions of the mechanism; a portion 45 of the side of the box is here broken away to give a clearer view of the position therewithin of the central follower piece. Fig. 4, is a sectional elevation of the feed box. Fig. 5, is an enlarged elevation of the 50 forward or feeding end of the box, showing the bristle-retarding finger and scraper. Fig. 6, is a perspective of the bristle-retarding finger. Fig. 7, is a perspective of the scraper, showing its adjustable character. Fig. 8, is a front perspective of the bristle- 55 retarding finger. Fig. 9, is a perspective of

the sweep, disassociated from all the other parts.

1 represents the bottom piece of the feed box, and 2 the cover. The sides 3 may be 60 moved inwardly or outwardly as desired, and are regulated by the engagement of bolts 4, which, engaging through the slots 6, may be screwed up to hold the side braces 5. In case the length of bristles used is 65 greater than ordinary, these side pieces, and the braces which are fixed to them, are moved outwardly as far as possible from the center of the box, thus allowing the bristles, which lie across the box, ample room to lie 70 exactly transversely to the lengthwise axis of the box as a whole. The bristles at the front, or feeding end, of the box are engaged by the slotted periphery of the picker or carrier *a*, as fully described in the patents 75 referred to. The extent of its periphery and of its swing in each cycle of operations is such that it at all times forms a complete bar to the egress of the bristles from that end of the box, except as taken by the slots 80 in the periphery of the carrier.

When the box is first filled, the central follower 61, which engages in tracks 7 and 8 in the cover and bottom piece, respectively, of the box, is pushed almost completely out 85 of the box, and the bristles arranged therein transversely of its length. The follower is then pushed against the rear end of this store of bristles (that is, farthest from the end engaged by the carrier), and caused to 90 press as heavily as necessary thereagainst by means of the weighted cord 9, which extends across the spreading piece 10 across the outer end of the follower 61, and passes over the spools 9^a. The follower 61 being 95 slideable lengthwise of the box, the pull of the weight at the bottom of the cord 9, which because of its extent over the spool 9^a is communicated equally to that part of the cord which bears against the spreading piece 10, which is fixed 100 to the follower piece 61, operates to push the follower piece as far within the box as the mass of bristles at its forward end will permit. This causes the mass of bristles, as it is diminished by the tufts taken by the carrier, 105 to be constantly pressed forward against the carrier; as the supply is diminished, the follower moves farther and farther within the box. A cross-brace or bolt unites the tops of the struts 12, and between these it passes 110 through the somewhat thickened end of the cover 2 and through the clamping finger 13,

whose inner end, extending back over the cover, is fixed thereto so as to move with the cover, and, when the box is closed, to lie almost parallel with the top of the follower. The opposite or free end of this clamping finger extends, when the box is closed, slightly beyond its end, and when the follower 61 is almost wholly within the box, overhangs the spreading piece 10. When the cover is raised, the free end of the clamping finger is by this movement lowered until it engages with its edge or point against the top edge of the follower, which when pulled out of the box along its track, lies directly therebeneath. By this time the cover is so nearly in a perpendicular position, that it may be left unsupported by the hand of the operator; the pressure of the finger upon the follower 61 is of such degree that, in spite of the pressure of the weighted cord 9, the follower cannot move forward until the cover is again swung to a horizontal position, and the pressure of the finger 13 against the top of the follower 61 comes to an end; this need not be done until the desired quantity of bristles has been inserted in the box forward of the front edge of the follower 61. When the cover is closed down it is held in place by means of the latch piece 14, which engages with its overhanging shoulder under that part of the bottom quite closely adjacent to one of the slots 6.

Bolted to a fixed portion 19 of the framework of the machine is a projecting bracket 20, whose outer end does not quite reach the forward edge of the mass of bristles in the feed box. As shown in Fig. 1, this bracket is pivoted to the rear of the framework of the machine, so that it lies behind, and to the rear of, the carrier member, shown in Fig. 2. Through the outer end of this bracket 20 passes a bolt 21, from which is pivotally suspended the engaging portion 22 of the sweep, whose engaging edge is normally almost parallel with the forward edge of the mass of bristles, and which is yieldingly held in that position by the spring 23. It being inevitable that the bristles used should vary somewhat in their size at various portions of their length, and as they thus, as a mass is advanced in the feed box, become more or less displaced from their proper position of exact perpendicularity to the longitudinal axis of the feed box, the sweep 22 is adapted to be forced against that side of the advancing mass formed by the large ends of the bristles, as they lie crosswise of the box; and, after each stroke of the carrier, which tends to exercise an increasingly displacing influence on the bristles, to force them back to their proper crosswise position. To accomplish this the pin 24 projects from the lower portion of the sweep as far as is desired, being regulated by the nut 24^a, into the path of the vertically reciprocating slide piece 25, whose

oblique shoulder portion 25^a engages against the pin 24 on each downward stroke, although it is not brought to a stop thereby, nor is it displaced from its path of travel, since it is controlled by fixed guide grooves 70 in the framework of the machine. The sweep 22 is, however, caused to strike forcibly against the edge of the mass of bristles, though its stroke is rendered very brief, because of the opposite pull of the spring 23. 75 It is, however, sufficient to impart the desired blow upon the too rapidly advancing ends of the bristles, and except at the extreme bottom of the pile suffices to hold them back sufficiently. 80

At the bottom and forward edge of the feed box is a partially bifurcated bristle-detaining finger 18, which is pivoted at 18^a to the forward ends of the guide flanges 8, between which the follower 61 engages, and which finger extends forward therefrom toward the picker or carrier *a*, so that its edge 17 just reaches to the forward edge of the box. It is preferably a unitary metallic member, whose side portions are united by a central web, which, together with these side portions, constitutes in effect a trough or track 17^a, coaxial with the lengthwise axis of the box along which, and through which, the follower 61, when pushed that far toward the 95 carrier *a*, engages. The free end of this finger is constantly pressed upward by a leaf-spring fixed to the bottom of the box, and extending therebeneath. The edges or points 17 which reach about the peripheral edge of 100 the carrier *a*, without, however, regardingly engaging the same, serve to scrape therefrom, and especially from the bristles carrying notches therein, any bristles which are not positively held thereby in satisfactory position for their delivery when united with the staple, and previous to their being driven into the brush back. Coöoperating with this, though its bracket is supported by the box bottom independently thereof, is the scraper 110 27, whose bracket 26 is fixed to the bottom of the box, so that the scraper or point 27 engages between the forked ends of the bristle-detaining finger 18, so as to just clear the peripheral edge of the carrier *a*; this, by engagement directly against the peripheral edge of the carrier, and in the same vertical plane, scrapes and keeps clear the portion of the carrier not cared for by the points 17 of the bristle detaining finger 18. The height 115 to which the scraper 27 extends toward the engaging edge of the carrier is regulated by the nut 27^a. 120

What I claim is:—

1. Feeding means for a brush making machine, comprising a supply box, means for forcing the bristles forward in a mass, the bristles being arranged across the feed box, means for removing bristles in tufts, an actuating slide therefor, a sweep adapted to be 125

positively actuated against the mass of bristles by the engagement thereagainst of the actuating slide, and means for quickly retracting the sweep from continued engagement against the bristles after each stroke thereagainst, substantially as described.

2. In a feeding device for a brush making machine, the combination of a bristle supply box having an open end wherein bristles are 10 adapted to be stored in a mass and to be pushed forward toward said open end as the space occupied by those bristles primarily nearest the same is vacated by their removal, a sweep pivotally supported transversely of the delivery end of said box, means for actuating the same against the exposed forward portion of the mass of bristles, and resilient means for retracting said sweep from continued engagement against the 20 bristles, substantially as described.

3. A feed device for a brush making machine having in combination a storage box wherein bristles are adapted to be laid in a mass across the box, a weighted follower 25 adapted to engage against one side of the store of bristles and force the same through the box, a reciprocating actuating member and a sweep member pivoted to a fixed portion of the machine and adapted to be swung by contact thereagainst of said actuating member against the forward portion of the store of bristles, the direction of its impact being substantially perpendicular to the line 30 of motion of the actuating moving portion of the machine, substantially as described.

4. A device adapted to periodically engage and force back into position a store of bristles, comprising a reciprocating portion of the brush making machine to which the 40 same is appurtenant a fixed suspending member, a pivotally supported engaging arm provided with a projecting portion adapted to be directly engaged by said reciprocating portion, and a spring adapted to 45 quickly restore the sweep member to its normal position after each stroke, substantially as described.

5. Bristle feeding means for brush making machines, comprising a receptacle open at 50 the ends wherein the bristles are adapted to lie crosswise thereof, a follower slidably engaging lengthwise therethrough, means for exerting pressure upon the outer end thereof, whereby the bristles are forced by its forward edge toward the delivery end of the receptacle, and a hinged cover piece adapted, when closed, to cooperate with the other portions of the receptacle in confining the 55 mass of bristles, and adapted when opened, to cause said follower to be held from movement in either direction, substantially as described.

6. In a device of the class described, in combination with a bottom piece provided 60 with longitudinal guide ways, adjustable side

pieces connected therewith, a pivoted cover piece provided with guide ways complementary to those of said bottom piece, a follower adapted to engage the guide ways in said bottom and cover pieces, means for forcing the same forward, and means controlled by the movement of said cover piece whereby the follower member may be held from further forward movement, substantially as 70 described.

7. In a device of the class described, in combination with a bottom piece provided with rising struts, a cover piece hinged to said struts and reaching over said bottom piece, the inner faces of each piece being 80 provided with complementary longitudinal guides, a follower member adapted to engage therein, and adjustable side pieces connected to said bottom portion adapted to operate with said follower member in the advancement of a supply of bristles toward one 85 end of the device, substantially as described.

8. In a device of the class described, in combination with a receptacle provided with adjustable sides open ends and a movable 90 cover, a follower member engaging lengthwise of said box and adapted to force the bristles toward the end of the box opposite to that entered by it, and means controlled by the movement of the cover whereby the 95 further advancement of the follower member may be arrested, substantially as described.

9. A bristle arranging device, having in combination with means for feeding bristles forward in a mass for engagement by a tuft 100 gatherer, a pivoted oscillatory arm adapted to be forced with sharp impact against said mass at certain intervals, means whereby it is quickly retracted from such position after the delivery of its stroke, and reciprocating 105 actuating means therefor, substantially as described.

10. In a device of the class described, in combination with a horizontally arranged receptacle having open ends, a slideable follower 110 member entering said receptacle through one of said ends and adapted to engage against a mass of bristles stored in said receptacle transversely thereof and to force them toward the other open end of the receptacle, and a bifurcated bristle-detaining finger pivoted to the bottom portion of the delivery 115 end of said receptacle, and means for resiliently supporting the same in substantially horizontal position with its engaging edge extending outwardly from its pivoted portion, in position to engage therewith all bristles not positively seized for removal from the receptacle, said finger being located in line with the path of travel of said follower member, and serving with its body portion as a guide thereto as it approaches the delivery end of the receptacle, substantially as described.

11. A bristle-containing receptacle for 120

brush making machines, comprising adjustable side pieces, a fixed bottom piece provided with a longitudinally extending guide channel, a movable top piece similarly channeled, a follower member engaging through said receptacle, being slidably held within the path of travel lengthwise of said receptacle by the channeled portions of said bottom and top pieces, a bifurcated finger pivotally attached to that portion of the delivery edge of the bottom piece nearest the

bristle removing member of the brush making machine, with its divided portion outermost, and means for resiliently supporting the same substantially as described.

In testimony whereof, I sign this specification in the presence of two witnesses.
